H. L. WILLIS

THREAD CUTTER FOR SEWING MACHINES

Filed Feb. 11, 1925

UNITED STATES PATENT OFFICE.

HARRY L. WILLIS, OF CHICAGO, ILLINOIS, ASSIGNOR TO UNION SPECIAL MACHINE COMPANY, OF CHICAGO, ILLINOIS, A CORPORATION OF ILLINOIS.

THREAD CUTTER FOR SEWING MACHINES.

Application filed February 11, 1925 Serial No. 8,467.

The invention relates to new and useful improvements in thread cutters for sewing machines, and more particularly to a cutter for cutting the enchain loops between 5 stitched articles.

An object of the invention is to provide a chain cutter which is so disposed relative to the stitching mechanism that the enchain loops may be swung into the thread 10 cutter and the threads cut at the same time when the material is moved laterally to remove it from the machine.

Another object is to provide a thread cutter with means for clamping the threads 15 extending between stitched articles prior to the severing of said threads and thus prevent the strain on the threads from springing the needle or disturbing the stitches or the thread loops so as to cause 20 a skipping of stitches.

Still another object of the invention is to provide the clamping member for clamping the threads with an opening therethrough arranged so that any lint accumu- 25 lating underneath the clamping member can work up through the opening, and thus permit the clamping member to freely clamp the thread in subsequent cutting operations.

These and other objects will in part be 30 obvious and will in part be hereinafter more fully disclosed.

In the drawings, which show by way 35 of illustration one embodiment of the invention:—

Figure 1 is a view of a portion of the front end of a sewing machine having the improvements embodied therein;

Fig. 2 is a section on the line 2—2 of Fig. 40 1, showing in dotted lines a stitched article and the manner of swinging the finished stitched article so as to carry the enchain loops leading from the stitched article to the stitching elements into the thread cutter 45 for clamping the ends of the severed threads;

Fig. 3 is a perspective view of a throat 50 plate and the improved thread cutter and clamp which is used in connection therewith.

The invention is directed broadly to a 55 thread cutter for severing the threads or enchain loops between stitched articles. This thread cutter includes a cutting member and a clamping member. The cutting member is so located that the operator, when

removing a stitched article from the machine, may by actual swinging of the article lay the connecting loops between stitched articles against the thread cutter and cut the threads. The thread cutter also includes 60 a clamping member which is located between the thread cutter and the needle for clamping the ends of the threads and holding the same so that the operator in pulling the enchain loops against the thread cutter will not unduly spring the 65 needle. This clamping member is also provided with an opening to allow any lint accumulating under the clamping member to escape and thus permit the clamping member to firmly clamp the threads. 70

Referring in detail to the drawings, the thread cutter is shown as applied to a sewing machine having a cloth plate 11, on which is mounted a throat plate 2. This throat plate is provided with a feed slot 75 3 in which a feed dog 4 cooperates. This is the ordinary feeding mechanism and further description thereof is not thought necessary.

The machine includes a needle bar 5 which is reciprocated in the usual way, and said needle bar is provided with a needle 6. Cooperating with the needle 6 is a threaded looper 6^a which is also of the usual construction. These stitching elements, that 80 is the needle and the looper, form the stitches for stitching the articles, and said elements will also form enchain loops between stitched articles. In other words, the machine is capable of chaining off 85 between stitched articles. The material is held on the work support by means of a presser foot 7 carried by the presser bar 8.

At one side of the feed slot 3 the throat plate is cut away at 9 to form a recess for 90 the shank 10 supporting the thread clamp and thread cutting member. The throat plate 2 is attached to the cloth plate 11 so as to form a right angle shoulder 12. The shank 10 lies in the recess 9 and extends 95 along the recess and up over the upper surface of the throat plate 2. The recess 9 gradually decreases in depth toward the rear end thereof so as to form a slight clearance 100 for the thread clamping member and, at the same time, allow the upper surface of the shank 10 to be flush with the upper surface 105 of the cloth plate at the forward end thereof,

said cloth plate being likewise raised to the level of the throat plate.

The shank 10 is provided with a thread clamping portion 13 which overlies the throat plate and is adapted to clamp a thread against the portion of the throat plate indicated at X in Fig. 3. The extreme rear end of this clamping member is turned up as indicated at 14. One side of the clamping member 13 is turned down as indicated at 15. This down-turned portion 15 lies along the shouldered wall 12 of the throat plate. At the extreme front end of the down-turned portion 15 there is a cutting edge 16.

At the other side of the clamping member 13 from the cutter 16 there is a projecting finger or arm 17 which extends across the rear end of the feed slot. This finger projects downwardly, as clearly shown in Fig. 3, and will extend into the feed slot in rear of the feed dog. The purpose of this finger is to guide the threads as they are drawn underneath the member 13 and against the thread cutter 16. The finger also serves to hold the enchain thread loops in a line extending directly back from the needle opening in the throat plate. The enchain thread loops are passed directly back until the finger is reached, and then will pass over the finger and underneath the thread clamp. This prevents the pulling on the enchain thread loops when cutting and clamping from being positioned at such an angle to the line of feed as results in a skipping of stitches. It also aids in the proper starting of the stitches in a piece of fabric when a new article is inserted in the machine. The shank 10 which carries the clamping member 13 is, of course, formed of steel and is bowed slightly, as shown in Fig. 1, so that the rear end thereof will bear against the upper face of the throat plate.

The enchain loops are indicated at *s* in the drawings. A stitched article is indicated at *S* as it passes out of the machine and at *S'* when the operator has swung said stitched article to bring the connecting threads or enchain loops *s* underneath the up-turned portion of the clamping member 13. It will be noted that this thread passes over the finger 17, thence underneath the up-turned portion 14, and then against the thread cutter where it is severed by a pull of the operator. The spring of the clamping member 13 holds the thread so tightly against the throat plate that a pull of the operator during the cutting of the threads is against the clamping member and not against the needle so as to spring the same.

When the thread is clamped, as above described, the pull of the operator on said thread during the severing of the thread will not disturb the enchain loops formed during the chaining off, that is stitching one

article to another. Furthermore, the clamping of the thread will hold the thread loops so that, if the needle thread loop is just being formed for the looper to enter, it will not be pulled so as to cause skipping of the stitches. This is very important in chaining off for, if one stitch is skipped, it is practically impossible to commence chaining again until the needle enters the fabric so that the material will aid in the forming of a thread loop for the looper to enter.

As the threads are drawn underneath this clamping member, the lint is often worked off from the thread and will accumulate underneath the clamping member. In order to prevent this, the clamping member 13 is provided with a hole 18 in the region of where the thread is clamped, and this hole permits the lint to work up through and escape, and thus it is that the clamp is kept free from an accumulation of lint and is always ready to engage and clamp the threads for a cutting operation.

The thread cutting mechanism is located in rear of the needle and at one side of the line of feed, and it is thus disposed so that, when the operator gives the stitched article the normal swing for removing it from the machine, the threads extending between the article and the stitching mechanism will be carried into contact with the thread cutter and severed.

It is obvious that minor changes in the details of construction and the arrangement of the parts may be made without departing from the spirit of the invention as set forth in the appended claims.

What is claimed as new is:—

1. The combination with a cloth plate, a needle, a feed dog and a presser foot, of a combined thread cutter and thread clamp secured to the cloth plate and located in rear of the presser foot and at one side of the line of feed whereby when the stitched article is swung on the cloth plate in the usual manner toward the front of the machine, the stitching threads are drawn beneath the thread clamp and against the thread cutter for severing the threads.

2. The combination with the needle, a feed dog, and a presser foot, of a combined thread cutter and thread clamping member, including a spring secured to the cloth plate at one side of the presser foot and extending along the same to a point beyond the rear end of the presser foot, said spring member having the rear end thereof up-turned and having a portion thereof turned down and formed with a cutting edge whereby when the stitched article is swung on the cloth plate in the usual manner toward the front of the machine, the stitching threads may be drawn underneath said up-turned end of the spring member and the thread clamped against the cloth plate by

the spring member, and the thread beyond the clamp drawn against the thread cutter and severed.

3. The combination with a needle, a feed dog and a presser foot, of a thread cutter located in rear of the presser foot and at one side of the line of feed whereby the stitched article may be swung to position the stitching threads extending from the 10 stitched article to the needle against the cutter for severing the threads, and a thread clamp between the cutter and the needle for clamping the threads before the severing takes place, said thread clamp having a hole 15 formed therethrough adjacent the point where the thread is clamped thereby in order to prevent lint from accumulating therein.

4. The combination of a needle, a presser 20 foot and a throat plate, said throat plate having a recess formed therein at one side of the presser foot, a metal shank secured to the throat plate in said recess and extending rearwardly over the upper surface 25 of the throat plate to a point well in rear of said needle, said recess being shaped so as to permit said shank at the rear end thereof to clamp a thread against the throat plate, and a thread cutter mounted on said shank 30 and extending downwardly at right angles thereto so that threads drawn underneath said shank will be brought into contact with said cutter.

5. The combination of a needle, a presser 35 foot and a throat plate, said throat plate having a recess formed therein at one side of the presser foot, a metal shank secured to the throat plate in said recess and extending rearwardly over the upper surface 40 of the throat plate, said recess being shaped so as to permit said shank at the rear end thereof to clamp a thread against the throat plate, a thread cutter mounted on said shank 45 and extending downwardly at right angles thereto so that threads drawn underneath said shank will be brought into contact with

said cutter, said shank having a projecting finger extending laterally therefrom and into the feed slot at the rear end thereof so as to direct the threads underneath said shank 50 for the clamping of the threads, said shank having the rear end thereof turned upwardly to aid in guiding the threads underneath the same and having a hole therein adjacent the clamping point for the threads to allow 55 lint to escape.

6. A sewing machine including in combination, a work support, a feeding mechanism, a presser foot, a needle, and a thread cutting and clamping device including a 60 supporting shank having a projecting finger substantially in rear of the needle over which the enchain thread loops may be laid when cutting and clamping, a thread cutting member located in rear of the presser foot and at one side of the line of feed, and a thread clamping member interposed between the finger and the cutter. 65

7. A sewing machine including in combination, a work support, a feeding mechanism, a presser foot, a needle, and a thread cutting and clamping device including a supporting shank having a projecting finger substantially in rear of the needle over which the enchain thread loops may be 70 laid when cutting and clamping, a thread cutting member located in rear of the presser foot and at one side of the line of feed, and a thread clamping member interposed between the finger and the cutter, said 75 80 thread clamping member having an upturned portion for guiding the enchain thread loops laid across said finger beneath the clamping member, said cutter being disposed below the plane of the clamping member so that when the enchain thread loops are passed underneath the clamping member they may be drawn against the cutter. 85

In testimony whereof, I affix my signature.

HARRY L. WILLIS.
